OF FLINT, MICHIGAN, A CORPORATION OF MICHIGAN.

SPARK-PLUG.

1,192,003.

Specification of Letters Patent. Patented July 25, 1916.

Application filed August 31, 1914. Serial No. 859,567.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark plugs and resides in the novel construction and arrangement of the electrodes therefor.

In the drawings,—Figure 1 is a longitudinal section through the lower end of the 15 spark plug, showing the electrodes in side elevation; and Fig. 2 is a section on the line $x-x$ of Fig. 1.

For obtaining a good spark it is essential 20 that the electrodes upon opposite sides of the spark gap should be either pointed or restricted *en masse*. On the other hand continued use will wear away the electrode, and it is quite customary to provide a double 25 spark gap to increase the amount of wearing surface. With my improved construction I provide electrodes having proper surfaces to produce an efficient spark and also provide sufficient wearing surface so that it is possible to employ but a single spark gap.

30 Referring to the one embodiment of the invention shown in the drawings, A is the metallic casing of the spark plug, B is the insulator therein, C is the insulated electrode which passes through the insulator 35 and extends downward therefrom, and D is a grounded electrode secured to the casing A. In the particular construction shown the electrodes C and D are provided with portions E and F that extend substantially parallel to each other for a considerable distance, providing a comparatively long spark gap. The length of the spark gap however, may be varied as desired. The electrodes are formed of round or similar cross-section, and 45 in order that the proper surfaces upon opposite sides of the spark gap may be had, the portions of the electrode between which the spark gap is formed have opposite sides thereof ground or milled down to form sub-

stantially knife edges G. This arrangement makes the surfaces of the electrode sufficiently sharp to produce a good spark.

It will be readily appreciated that my invention may be embodied in various constructions and that it is only necessary to 55 shape those portions of the electrodes which are upon opposite sides of the spark gap, though of course, the entire projecting portions of the electrode might be ground or milled if so desired.

60 What I claim as my invention is:—

1. In a spark plug, coöperating electrodes having portions formed of an approximate wedge shaped section providing longitudinally extended thin edges opposite and substantially parallel to each other and in substantially the same plane.

2. In a spark plug, a plug and coöperating electrodes each having portions extending obliquely of the longitudinal axis of the plug 70 and opposite and substantially parallel to each other, said portions being of an approximate wedge shaped cross section providing thin edges on opposite sides of the spark plug.

3. In a spark plug, an insulated electrode having a return bent portion and a portion extending upward obliquely of the longitudinal axis of the spark plug, a coöperating electrode extending downward obliquely of the longitudinal axis of the spark plug, said electrodes being formed of a wedge shaped cross section in their oblique portions forming thin edges arranged opposite and substantially parallel to each other in the plane of the spark gap.

4. In a spark plug, an electrode having a portion extending obliquely of the longitudinal axis of the plug, said portion being provided with a thin longitudinally extended edge and a coöperating electrode having a portion provided with a corresponding thin longitudinally extending edge substantially in the plane with said first-mentioned portion, said thin longitudinally extending edges being substantially opposite and parallel to each other.

ALBERT SCHMIDT.
